UNITED STATES PATENT OFFICE.

MALVIN LICHTER, OF NEW YORK, N. Y., ASSIGNOR TO SAID MALVIN LICHTER AND LOUIS JACOBS, PARTNERS TRADING AS STICKLESS FAN COMPANY, OF NEW YORK, N. Y.

FAN.

Application filed July 6, 1921. Serial No. 482,727.

To all whom it may concern:

Be it known that I, MALVIN LICHTER, a citizen of the United States, residing in New York, county of New York, and State of New York, have invented certain new and useful Improvements in Fans, of which the following is a full, clear, and concise description.

My invention relates to fans, and more particularly to hand fans of the general type disclosed in my patent of February 2, 1915, No. 1,126,797.

By my invention now under contemplation, I seek to increase the flexibility of the fan blade, at various points in close proximity to the handle, and at the same time give the handle and parts immediately adjacent thereto a maximum of stiffness and strength.

I also seek to so construct the fan as to render it more comfortable in feeling when grasped by the hand of the operator, in actual use in fanning.

In addition, I seek to give certain parts of the fan such form as to facilitate their manufacture in quantity and render them easy to standardize.

Reference is made to the accompanying drawing forming a part of this specification, and in which reference characters indicate like parts throughout the several figures.

Figure 1 is a view of one form of my improved fan, and shows the same partly in elevation and partly as with certain parts broken away.

Figure 2 shows either form of my fan, as it appears when held in the hand of the operator, ready for use.

Figure 3 is a section on the line 3—3 of Figure 1, looking in the direction indicated by the arrows.

Figure 4 is a fragmentary section somewhat similar to Figure 3, but showing a form of the fan different from that appearing in Figure 1.

Figure 5 is a fragmentary elevation indicating the manner in which a number of handle members are successively cut from a single piece of stock, so as to avoid waste.

The blade of the fan appears at 6, and is provided with a curved edge 7, in this particular instance substantially semicircular. The blade is provided with a projecting por-

tion 8, neatly curved and otherwise formed and adapted to fit into the palm of the hand, when the fan is grasped in the usual manner, as indicated more particularly in Figure 2. The blade 6 is provided with a thumb-hole 9.

In the form shown in Figures 1 and 3, the blade 6 is sandwiched between two handle members 10, exactly alike and having the form shown. The thumb-hole 9 is spaced slightly away from the adjacent portions or inner edges of the handle members 10, so as to leave a portion 9^b of the blade, in immediate proximity to the thumb-hole 9 and also in immediate proximity to the handle members 10, in such form as to have a certain degree of flexibility and resilience, coupled with a reasonable amount of stiffness and strength. That is to say, the portion 9^b can flex or bend a little, and when so flexed or bent has a tendency to return to its initial position relatively to other parts, and yet the portion in question is in great measure re-enforced, stiffened and strengthened because of its proximity to the two handle members 10, between which the blade is sandwiched as above described. Thus the portion 9^b serves in a capacity more or less analogous to that of a cushion.

Each handle member 10 is at its extremities provided with straight edges 11 which are exactly parallel with each other. The blade 6 is provided with a pair of scalloped edges 12; and between each edge 12 and the straight edge 11 immediately adjacent thereto is a substantially V-shaped portion 13 of the blade 6, this V-shaped portion having a certain amount of stiffness and strength conferred upon it in consequence of its proximity to the ends of the two handle members 10, disposed upon opposite faces of the blade 6. Thus the portion 13 is in some respects like the portion 9^b above described. While it has some resilience and flexibility, it is quite strong; and it is so arranged as to render more gradual than would otherwise be the case the bending of the fan as a whole. In other words the part 13, because of its width at the top serves to distribute the stresses arising when the blade is bent or sprung back and forth due to the ordinary use of the fan, and in this way the blade is not so likely to be broken or creased from such stresses. Thus the life of the fan

is greatly prolonged. The form of the part 13 and the relation of this part to the two handle members 10 contribute toward preventing any bending action of the blade 5 from becoming unduly localized.

The blade 6 is further provided with a portion 9^a which extends slightly outward from the outer or rounded edges of the handle members 10, so as to form a margin 10 which protrudes slightly, as indicated more particularly in Figures 1 and 3. This protruding portion or margin serves a good purpose, in cushioning the fan against blows and crushing pressures of various kinds, 15 which would otherwise be received upon the edges of the handle members 10 directly. The principal use of the protruding portion 9^a, however, is to confer upon the handle of the fan such form as to render the feeling 20 of the handle more agreeable to the operator by whom it is grasped. This may be understood more particularly from Figure 2, which shows the fan as grasped by the operator's hand 14, the operator's thumb 15 extending through the thumb-hole 9, the protruding portion 9^a fitting neatly into the palm of the hand. As may be readily understood from this figure and from the form 25 of the parts as shown in cross section at the bottom of Figure 3, the handle of the fan fits into the hand of the operator quite neatly and agreeably to the touch. Moreover, if for any reason, the operator's grasp 30 is tightened the protruding portion 9^a is slightly sprung or flexed, the pressure of the hand being thus to some extent cushioned, and the pressure being so distributed as to 35 avoid all disagreeable sensation to the operator's hand.

40 The above-mentioned advantages are in part due to the form of the handle members 10. An additional advantage due to the form of these members is that they can be cut one at a time from a single piece of 45 stock without waste, except possibly at the ends of the piece, as shown at 16 in Figure 5.

In the form of my device shown in Figure 4 the structure and action of the various parts is the same as in Figures 1 to 3 inclusive, except that in Figure 4 one of the handle members 10 is omitted. This gives a somewhat lighter and cheaper construction, but one in which the re-enforcing of the blade is not quite so pronounced.

55 I preferably make the blade 6 and the handle members 10 of cardboard, these parts being secured together by means of glue, cement or other appropriate adhesive. However, I do not wish to limit myself to 60 the use of any particular materials, nor to the precise construction shown, as varia-

tions may be made therein without departing from my invention, the spirit of which is commensurate with my claims.

Having thus described my invention, what I claim as new and desire to secure by Letters Patent is as follows:

1. In a hand fan, the combination of a blade made of cardboard and provided with a thumb hole, and a pair of handle members 70 made of cardboard and located upon opposite faces of the blade in such position as to clear the thumb hole, the handle members and the intervening portion of the blade each being formed to fit neatly into the palm 75 of the operator's hand while the thumb of the same hand is occupying the thumb hole.

2. In a hand fan, the combination of a blade made of sheet material and a pair of handle members made of sheet material and 80 secured upon opposite faces of the blade, said blade and each of said handle members being provided with an edge portion conforming in profile to the palm of the hand, the said edge portion of the blade being displaced relatively to the adjacent edge portions of the handle members, so as to leave the said edge portion of the blade protruding slightly from the said edge portions of the handle members. 85

3. In a hand fan, the combination of a blade made of sheet material and a pair of handle members made of sheet material and secured upon opposite faces of the blade, said blade and each of the handle members 95 being provided with an edge portion conforming in profile to the palm of the hand, each handle member being provided with a pair of straight edges parallel with each other, and the blade being provided with a 100 pair of edge portions disposed adjacent said straight parallel edges and diverging therefrom, in order to distribute to better advantage the stresses arising within the blade when the fan is subjected to a bending 105 strain.

4. In a hand fan the combination of a blade having an edge portion so curved as to conform in profile to the palm of the hand and having an opening suitable for 110 receiving the thumb, and a handle member made of sheet material and secured upon the blade in such position as to clear said opening, said handle member having an edge portion so curved as to conform in profile to the palm of the hand, this portion of the handle member being disposed in close 115 proximity to said edge portion of the blade, so curved as to conform in profile to the palm of the hand.

MALVIN LICHTER.
